UNITED STATES PATENT OFFICE.

PATRICK J. COLLINS, OF SCRANTON, PENNSYLVANIA, ASSIGNOR, BY
MESNE ASSIGNMENTS, TO GENERAL ELECTRIC COMPANY, A COR-
PORATION OF NEW YORK.

ELECTRIC RAILWAY-MOTOR.

No. 826,315.

Specification of Letters Patent.

Patented July 17, 1906.

Application filed January 3, 1905. Serial No. 239,345.

To all whom it may concern:

Be it known that I, PATRICK J. COLLINS, a citizen of the United States, residing at Scranton, in the county of Lackawanna and State of Pennsylvania, have invented certain new and useful Improvements in Electric Railway-Motors, of which the following is a specification.

This invention relates to improvements in electric motors of the type shown in my prior patents, No. 655,852, dated August 14, 1900, and No. 725,675, dated April 21, 1903, in which two or more armatures are arranged within a surrounding field-frame, which is divided into two or more compartments by a transverse partition or partitions extending between adjacent armatures, each of said partitions forming a part of the magnetic circuit and having pole-pieces thereon adjacent to the armatures. In the present application a multiple motor of this character is arranged for railway traction purposes, the field-frame of the motor forming also a part of the truck-frame.

In the accompanying drawings, Figure 1 is a plan view of a four-wheeled motor-truck embodying my invention, field-windings being shown only upon one pole-piece within each compartment of the field-frame. Fig. 2 is a section on the line 2 2 of Fig. 1. Fig. 3 is a side elevation of the truck shown in Fig. 1. Fig. 4 is a section on the line 4 4 of Fig. 3, the armature being shown in elevation. Fig. 5 is a plan view of a four-wheeled motor-truck, the arrangement being the same as in Fig. 1, except that field-coils are arranged upon both pole-pieces in each compartment of the field-frame. Fig. 6 is a similar view of a six-wheeled truck. Fig. 7 is a plan view of a six-wheeled truck, showing two armatures upon each car-axle, each pair of armatures having a commutator common to both.

Referring to Figs. 1 to 4, inclusive, of the drawings, A indicates a rectangular field-frame of iron or steel, having side bars a connected by a central transverse partition a' and end bars a^2 , which are suitably connected to the end bars b^2 of an outer rectangular frame B. The side bars b' of the outer frame are suitably supported upon journal-boxes 1 at the ends of a pair of car-axles 2 and 3 outside of the car-wheels 4, and the side bars a of

the inner frame are also preferably supported upon bearings 5, resting upon the axles at the inner sides of the wheels.

55

Upon the car-axles and within the compartments C and C' of the inner frame, formed by the partition a' , are arranged armatures D, which are suitably secured to the axles so that the latter may be turned by the armatures. Pole-pieces 6 and 7, connected to the partitions a' , project toward the armatures in the compartments C and C', respectively, and opposing pole-pieces 8 and 9, respectively, are arranged upon the end bars of the field-frame A at the opposite sides of the armatures. The inner pole-pieces 6 and 7 are provided with windings 10, and when current is passed through these coils or windings consequent poles are formed in the pole-pieces 8 and 9. 60 As in my prior patents referred to, the magnetic circuits for both motors extend through the partition between the armatures and through the side and end bars of the field-frame A. 65

70

When the direction of the current in the windings is such as to produce poles of opposite sign in the ends of the pole-pieces 6 and 7, and consequently poles of opposite sign in the end pieces 8 and 9, the side and end bars of 80 both frames, as well as the partition a' , then form parts of the magnetic circuit.

75

In Fig. 5 the construction is the same as in Fig. 1, except that field-windings 10^a are arranged upon the end pole-pieces 8^a and 9^a, as 85 well as upon the pole-pieces 6^a and 7^a, secured to the partition a' , whereas in Fig. 1 the windings are upon the inner pole-pieces only.

In Fig. 6 a six-wheeled truck is shown, the 90 frames A' and B' being extended and the former having two partitions a' , dividing the field-frame into three compartments C, C', and C². Each partition carries pole-pieces 6^a and 7^a, surrounded by coils 10^a and projecting in opposite directions toward armatures D, arranged upon car-axles in the adjacent compartments. Pole-pieces 8^a and 9^a are arranged upon the end bars of the frame A' and surrounded by coils 10^a, the same as in Fig. 5. In Fig. 6 each partition a' forms part of the magnetic circuit for two motors, the arrangement being substantially the same as in Fig. 5, except that the frames 95 100

are extended and an additional partition and pair of pole-pieces provided for the additional armature upon a six-wheeled motor-truck.

In Fig. 7 the frames are the same as in Fig. 5 6; but each partition carries a pair of pole-pieces 6^b and 7^b, projecting into adjoining compartments, and pairs of pole-pieces 8^b and 9^b are arranged at the ends of the field-frames. Between the opposing pole-pieces 10 in the several compartments are arranged upon each axle two armatures D' and D². These armatures are secured to the axles, and a single commutator 13 suffices for each pair of armatures.

15 Any desired number of axles and partitions with pole-pieces between the axles may be added to the truck, and for such purposes, as transfer-tables, where extended axles are provided with more than two wheels to run 20 on several tracks, more than two armatures may be placed on each axle, the pole-pieces on the transverse bars of the frame being correspondingly increased and the longitudinal partitions being also increased, if desired.

25 What I claim as new, and desire to secure by Letters Patent, is—

1. In a motor-truck, the combination with axles having wheels thereon, armatures upon said axles and a main truck-frame supported 30 upon the ends of said axles, of a field-frame having side bars extending longitudinally of the truck-frame between the ends of the armatures and the wheels, said field-frame having also a transverse partition arranged between each adjacent pair of armatures, pole-pieces upon each of said partitions, and pole-pieces at the ends of the field-frame.

2. In a motor-truck, the combination with axles having wheels thereon, armatures upon 40 said axles and a main truck-frame supported upon the ends of said axles, of a field-frame secured to the main frame, and having side bars extending longitudinally of the truck-frame between the ends of the armatures and the wheels, said field-frame having also a transverse partition arranged between each adjacent pair of armatures, pole-pieces upon each of said partitions, and pole-pieces at the ends of the field-frame.

50 3. In a motor-truck, the combination with axles having wheels thereon, armatures upon said axles and a main truck-frame supported upon the ends of said axles, of a field-frame having end bars secured to the main frame, and having side bars extending longitudinally of the truck-frame between the ends of the armatures and the wheels, said field-frame having also a transverse partition arranged between each adjacent pair of armatures, 55 pole-pieces upon each of said partitions, and pole-pieces upon the end bars of the field-frame.

4. In a motor-truck the combination with axles having wheels thereon, armatures upon 60 said axles, and a main truck-frame supported

upon the ends of said axles, of a field-frame having end bars secured to the ends of the main truck-frame, side bars extending between the ends of the armatures and the wheels, a transverse partition extending between each pair of adjacent armatures, pole-pieces upon the end bars of the field-frame, and bearings upon the axles arranged to support the side bars of the field-frame.

5. In a motor-truck, the combination with 75 axles having wheels thereon, armatures upon said axles and a rectangular steel or iron main truck-frame supported upon the ends of the axles at the outer sides of the wheels, of a rectangular field-frame having its end bars 80 secured to the ends of the main truck-frame and its side bars extending between the ends of the armatures and the wheels, a transverse partition extending between each adjacent pair of armatures, pole-pieces upon each of 85 said partitions and pole-pieces upon the end bars of the field-frame.

6. In a motor-truck, the combination with axles having wheels thereon, two armatures upon each of said axles and a main truck-frame 90 supported upon the ends of said axles, of a field-frame having side bars extending longitudinally of the truck-frame between the ends of the armatures and the wheels, said field-frame having also a transverse partition 95 arranged between each adjacent pair of armatures, pole-pieces upon each of said partitions, one pole-piece for each adjacent armature, and pole-pieces at the ends of the field-frame opposite the adjacent armatures.

7. A motor-truck having in combination, driving-axles, motor-armatures supported upon said axles, a truck-frame mounted upon said axles, and a motor field-frame carried by said truck-frame and provided with pole-pieces adjacent the several armatures.

8. A motor-truck having in combination, driving-axles, motor-armatures supported upon said axles, a main truck-frame mounted upon said axles and a motor field-frame having side bars extending longitudinally of the truck-frame and transverse members, and pole-pieces carried by said transverse members in operative relation to the several armatures.

9. A motor-truck having in combination, driving-axles, motor-armatures supported upon said axles, a main truck-frame composed of magnetic material mounted upon said axles, a motor field-frame secured to said 120 main frame at the ends thereof and provided with pole-pieces supported in operative relation to the several motor-armatures.

In testimony whereof I affix my signature in presence of two witnesses.

PATRICK J. COLLINS.
